UNITED STATES PATENT OFFICE.

JAMES HARVEY STRONG, OF STEUBENVILLE, OHIO.

DESIGN FOR A REFLECTOR-SHADE.

44,620.

Specification for Design.

Patented Sept. 2, 1913.

Application filed March 9, 1912. Serial No. 682,789. Term of patent 7 years.

To all whom it may concern:

Be it known that I, JAMES HARVEY STRONG, a citizen of the United States of America, and a resident of Steubenville, in the State of Ohio, have invented a certain new, original, and ornamental Design for Reflector-Shades, of which the following is a specification.

In the drawing Figure 1 is an elevation. Fig. 2 is a bottom plan.

The shade, as shown, has on its outer surface a plurality of groups 1 of angular prisms. These prisms converge toward their upper extremities, forming a single prism, so that each group has a single vertex 2 adjacent the top of the shade. The

groups are spaced apart, and between each two groups is a convexly curved flute 3. These are the important features of my invention.

The groups as shown consist each of three prisms, the central prism 4 being considerably larger than either of the other two.

I claim:

The ornamental design for a reflector shade as herein shown and described.

Signed by me at Steubenville in the State of Ohio this 1st day of March, 1912.

JAMES HARVEY STRONG.

Witnesses:

H. B. GRIER,
D. REHM ROOKE.
